GAME BOARD OR SIMILAR ARTICLE

Ralph Louis Cobb, Charlotte, N. C.

Application September 14, 1955, Serial No. 37,920

Term of patent 14 years

(Cl. D34—5)

The single figure is a top plan view of a game board or similar article, showing my new design.

The game board is of no appreciable thickness, and the back thereof is plain or unornamented.

The dominant features of my new design are shown in solid lines in the drawing.

I claim:

The ornamental design for a game board or similar article, as shown and described.
